UNITED STATES PATENT OFFICE

2,023,557

SLUG CASTING MACHINE

Anthony J. Stouges, Queens Village, N. Y., assignor to Mergenthaler Linotype Company, a corporation of New York

Application June 22, 1934, Serial No. 731,832

29 Claims. (Cl. 199—52)

This invention relates to slug casting machines and is directed to certain improvements which will adapt the machine to accommodate hand sticks varying in form in accordance with different forms of matrices, as for instance the regular linotype matrices formed with projecting ears on their opposite edges, large special matrices devoid of such projecting ears, and other special matrices formed with projecting ears at their upper and lower ends (commonly known as Ludlow matrices).

In the use of the improved machine, the matrices are composed in line in a hand stick which is then placed in a holder in the machine and thereafter presented automatically to the casting mechanism which is equipped with molds of different forms to cooperate with the different forms of matrices employed. In the particular embodiment illustrated, the holder is the vertically movable transporter or first elevator which has a front plate adapted to accommodate several of the different forms of hand sticks, and which is arranged to be equipped with a removable section to adapt it to hold other forms of hand sticks.

Each of the hand sticks is equipped with a movable end wall and mechanism for preliminarily applying clamping pressure to the line composed therein through said wall to facilitate handling prior to placing the hand stick in the machine. The hand stick is then placed upon a table in endwise alinement, with the first elevator or transporter and bodily inserted therein. The transporter thereupon descends to position the hand stick between the vise jaws mounted in the vise frame, the line brought into registry with the mold by the adjustment of the vise jaws, which at the same time adjust the clamping pressure on the line through the movable end wall of the stick, the mold disc moved forwardly to bring the face of the mold in contact with the casting edges of the matrices, and the mold filled with molten metal to form a slug against the matrices which produce the type characters thereon. After the casting operation, the elevator ascends to its normal position and the hand stick ejected from the transporter by a manually operable slide.

The invention also contemplates further improvements, as for instance, a keeper plate in one form of hand stick, automatically adjustable into engagement with notches provided in the alining surfaces of the matrices used therewith to prevent the latter from being displaced from the hand stick during casting, an adjustable plate on

the table to assist in alining the hand stick with the transporter and which is adjusted to active position when the transporter is provided with the removable section and to inactive position when not so provided, and improvements in the transporter arresting blocks, which not only permit the composed line to be presented to the mold at any desired casting level depending upon the form and size of the matrices and the particular mold in use, but which also permits the faces of the slugs to be adjusted transversely of the mold slot by any amount desired, as for instance, in casting slugs with large type faces and small body sizes.

Referring to the drawings:

Fig. 1 is a front view of a portion of the improved machine, showing a hand stick in position for delivery to the transporter, and wherein the position of the stick in the transporter is indicated by dotted lines;

Fig. 2 is a horizontal section of part of the mechanism illustrated in Fig. 1, and showing the general arrangement of the parts and the stick in front of the mold before casting;

Fig. 3 is a vertical section taken on line 3—3 of Fig. 2, showing the stick positioned between the vise jaws;

Fig. 4 is a view similar to Fig. 3, showing the stick clamped between the vise jaws;

Fig. 5 is a vertical section through the first elevator and the casting mechanism;

Fig. 6 is a rear view taken on line 6—6 of Fig. 5, the transporter being broken away to show details of construction;

Fig. 7 is a vertical section taken on line 7—7 of Fig. 6;

Fig. 8 is a perspective view of the removable transporter section for sustaining certain of the different forms of sticks used;

Figs. 9, 10 and 11 are perspective views of the different forms of matrices employed;

Fig. 12 is a perspective view of a reversible spacer used with the form of matrix shown in Fig. 9;

Fig. 13 is an elevation of one of the hand sticks employed, parts being broken away to show details of construction;

Fig. 14 is an end view of the stick shown in Fig. 13;

Fig. 15 is an elevation, partly in section, of another form of hand stick;

Fig. 16 is an end view of the hand stick shown in Fig. 15;

Figs. 17 and 18 are sectional views through the transporter, showing the different forms of sticks

employed for two different sizes of one special form of matrix:

Figs. 19 and 20 are sectional views through the transporter, showing the different forms of sticks employed for the regular linotype matrices:

Figs. 21 and 22 are sectional views, partly in elevation, showing the transporter in its upper or normal position, and showing also two special forms of matrices, one used with and the other without the transporter removable section;

Fig. 23 is a top plan view of one form of dial plate for adjusting the position of the banking stops in accordance with the different forms of matrices employed:

15 Fig. 24 is a side view, partly in section, of the dial plate shown in Fig. 23:

Figs. 25 and 26 show, respectively, the opposite faces of a different form of dial plate:

Figs. 27 and 28 are, respectively, side views, partly in section, of the dial plates shown in Figs. 25 and 26, illustrating the method of mounting the same; and

Fig. 29 is a view of the casting edges of four matrices, showing the difference in alinement of the matrices depending upon the length of the lower case descenders.

The disc A, see Fig. 1, is rotatably mounted,

as usual, on a fore-and-aft mold slide (not shown), and is equipped with four slotted molds, 30 any selected one of which may be brought into use by the rotary adjustment of the disc A by the manual operation of the usual driving pinion A¹. As the machine is started, the mold disc is given a quarter turn in a counter-clockwise direction 35 (looking from the front of the machine) to locate the selected mold in the casting position. The first elevator or transporter B then descends to position a line of matrices supported in a hand stick in the transporter (previously inserted 40 therein) in front of the active mold, whereupon the line is justified in the stick between a pair of clamping jaws C¹, C² mounted in the fixed vertically disposed vise frame D. The mold slide is now moved forward to bring the active mold up 45 against the composed line, thereby closing the mold slot at the front, and the metal pot is likewise advanced from its normal position behind the disc A to bring the mouthpiece thereof up against the back of the mold, thereby closing the 50 mold slot at the rear. The descent of the pot plungers immediately follows and molten metal is ejected from the pot into the mold to produce the slug. After the casting operation, the pot and mold are caused to recede, the transporter 55 B is raised, and the active mold is carried to the slug ejecting position. As the machine completes the cycle of operation, the slug is ejected from the mold and the transporter B is finally arrested in its original or uppermost position.

60 The regular matrices Y and Y^1 (see Figs. 11,
19 and 20) are formed with the upper projecting
ears y and the lower projecting ears y^2 . The ma-
trices Y are provided with two superposed char-
acters y^3 confined to the smaller text fonts rang-
ing below 14 pt., while the matrices Y^1 are pro-
vided with but a single character y^4 confined to
the larger head-letter and display fonts above 14
pt. The characters of the regular matrix fonts
are positioned as usual, and for reasons well
70 known, with reference to a common datum line
for top alinement, whereas the characters of the
special fonts X , X^1 , and which have a range up
to 72 pt. in height in the instance of the matrices
 X^1 , and up to 144 pt. in height in the instance
75 of the matrices X , are positioned with reference

to a common datum line for base alignment, so that the matrices may be mixed indiscriminately in the same line, irrespective of the height of their individual characters.

The special matrices X^1 (Figs. 9 and 21) are formed on their bottom edges with alining surfaces x^2 , and in their casting edges with recesses or routing notches x^3 , which are preferably of a depth to compensate for the reduced depth of special molds used with these matrices. The special matrices X^1 are further formed in their bottom alining edges with transverse notches x^4 , which are adapted to receive the top edge of a rail member provided in the hand stick in which these matrices X^1 are composed, and which acts to prevent displacement of the matrices from their supporting ledges in the hand stick during the casting operation. 5 10 15

The special matrices X (Fig. 22) are formed in their rear edges with recesses x^5 , the upper faces of which present under alining surfaces x^6 at the same level as the alining edges x^2 of the special matrices X^1 . The alining surfaces x^6 are likewise provided with transverse notches x^7 corresponding to the notches x^4 in the matrices X^1 and for the same purpose. The matrices X are also formed in their casting edges with recesses or routing notches x^8 . These recesses extend considerably below the alining surfaces x^6 to accommodate the larger characters, and, in the front or casting edges and adjacent sides thereof, these matrices may further be provided with walls extending upwardly from the lower edges slightly beyond the level of the alining surfaces x^6 , so that when these larger matrices are composed in line with the matrices X^1 the routing notches or recesses therein are closed off in that portion which extends below the base of an adjacent matrix to prevent metal squirts. Matrices of this form are more specifically described in my copending application, Serial No. 670,712, filed May 12, 1933.

Both the matrices X and X^1 are further provided in their upper edges with recesses x^9 adapted to receive the lower edge of the line transporter back plate, which, together with the rails in the 45 hand sticks engaging in the notches x^4 and x^7 , serve to retain the matrices against displacement from the stick.

A blank matrix or spacer element X^3 for use with the special matrices X^1 is illustrated in Fig. 50 12. This spacer element is reversible and for this purpose is provided in its lower edge with a pair of recesses or notches x^{10} , and in its upper edge with a pair of recesses or notches x^{11} , one each of the notches x^{10} and x^{11} alining with the 55 notches x^4 and x^9 of the special matrices when composed in line therewith. The spacer element X^3 is further provided in its upper edge with a lug x^{12} projecting above the upper edges of the matrices composed in line therewith to facilitate 60 handling.

The special or Ludlow matrices Z, Z¹ (Figs. 10, 17 and 18) are formed on their upper edges with upwardly projecting ears z², and on their lower edges with alining surfaces z¹ and downwardly 65 projecting ears z⁵; the ears z² and z⁵ serving to position the matrices in the hand stick. The matrices Z, Z¹ are also provided in their casting edges with recesses or routing notches z⁶ which are likewise of a depth to compensate for the 70 reduced depth of the special molds used with these matrices.

The line transporter or first elevator B (Fig. 1 and Fig. 5) comprises the elongated vertically disposed body portion B¹ slidably mounted in the 75

fixed vise frame D, the top flange B² which overhangs said frame, and the horizontally disposed head portion B³ which depends from the rear edge of the flange B². The head portion B³, wherein the hand sticks are sustained, consists of the front and rear side walls B⁴ and B⁵ and intermediate spacing blocks B⁶ and B⁷ positioned at opposite ends thereof.

The hand sticks, of which there are six different forms illustrated herein to sustain the matrices of different forms, are transferred from a table M arranged at the normal transporter level endwise into the transporter from the right. As a stick is inserted in the transporter, it is located endwise therein by a block b⁸ in a position to bring it between the customary vise jaws C¹, C² when the transporter B descends to present the composed line to the mold. The transporter is arrested in its descent in different positions dependent upon the particular form and size of matrices in use. More will be said of this later.

Certain forms of hand sticks, as for instance, those used with the special matrices X and the regular matrices Y, Y¹, are supported directly in the transporter, whereas those used with the special matrices X¹, Z and Z¹ require the presence of a removable filler section E to adapt the transporter to receive the hand sticks of these latter forms. To support the hand sticks or the removable section E, as the case may be, there is provided in the front wall B⁴ of the transporter, a recess B⁸ presenting a horizontal supporting ledge B⁹ at the bottom and a horizontal upstanding keeper plate B¹⁰ at the outer edge of the ledge.

The removable filler section E (see Figs. 5 and 8) is substantially L-shape in cross section and includes in part a body portion E¹ of the same width as the transporter recess B⁸, a lower horizontal portion E², arranged to rest upon the supporting ledge B⁹ of the transporter and provided with a longitudinal recess E³ in which the keeper plate B¹⁰ engages to hold the removable filler section E in position. The lower portion E² of the section E likewise presents a supporting ledge E⁴ formed at its outer edge with an upstanding keeper E⁵ to sustain the hand sticks which require the presence of the removable section E. The removable section E is detachably secured against endwise displacement in the transporter, and for this purpose it is provided at its left end (looking at the machine from the front) with an extension E⁶ adapted to underlie the spacer member B⁶ of the transporter and equipped at its outer end with a bevelled surface E⁷ and a notch E⁸ which cooperates with a retractable pin b extending vertically through the front wall portion B⁴ of the transporter immediately above the recess B⁸. The retractable pin b is slidably mounted in a recess b¹ and includes generally an enlarged portion b² engaging the walls of the recess, a smaller shank portion b³ encircled by a compression spring b⁴ engaging between the upper end of the enlarged portion b² and the upper end of the recess, and a knurled button or handle b⁵ screwed to the shank b³ at its upper end and which rests upon the upper face of the transporter, thus determining the lowermost position of the pin. As the removable section E is inserted in the transporter from the left, the pin b will ride up the bevelled surface E against the compression of the spring b⁴ and when the pin b registers with the notch E⁸ it will engage therein and hold the filler section E against endwise movement in the transporter. To remove the

filler section E, it is necessary only to pull up on the button b⁵, thereby withdrawing the pin from the notch E⁸ and freeing the filler plate so that it may be withdrawn endwise from the transporter.

A hand stick F for use with the special matrices X¹, is shown in Figs. 13, 14 and 21, and includes in part a top and a bottom rail F and F², a rear closing plate F³, a pair of fixed end walls F⁴ and F⁵, notched on their rear edges to receive the rails F¹, F² to which the end walls are secured, and a movable line adjusting wall member F⁶ adjustably held in the stick by a headed pin F⁷ threaded into the movable wall member F⁶ and extending through a bushing member F⁸ threaded through the fixed wall member F⁴. When a line has been composed in the stick, initial pressure for locking it therein is applied by screwing up on the bushing F⁸ which butts against the wall member F⁶. This pressure, of course, may not be sufficient for proper justification of the line, but the deficiency, if any, is supplied by the right hand jaw C², which during the alinement of the composed line with the mold slot prior to casting acts on the pin F⁷ to adjust the clamping pressure independently of the bushing F⁸.

As clearly shown in Fig. 13, the bushing member F⁸ is formed with a plain neck portion F¹¹ traversed at its lower side by a detachable plate F¹², which latter serves by engagement with the threaded portion to prevent the bushing member from being unscrewed far enough to engage the right-hand jaw when the hand stick is placed in position for casting. In this way the casting is always controlled by the headed pin F⁷ as intended.

The front edges of the end walls F⁴, F⁵, as well as the movable plate F⁶ register with the front or casting edges of the matrices, the end wall F⁶ and the movable wall member F⁶ acting to close the line of matrices at the ends. Like the matrices, the end walls F⁴, F⁵ and the movable wall member F⁶ are provided in their front upper portions with recesses or notches F⁹ to fit the rear wall B⁵ of the transporter and which assists in holding the stick in the transporter. The end walls F⁴, F⁵ terminate at their lower edges slightly above the bottom surface of the lower rail F², thus providing the necessary clearance for the keeper element E⁵ of the removable section E to engage the rail as shown in Fig. 21. The bottom edge of the lower rail F² constitutes the alining surface of the hand stick, and rests in service on the supporting ledge E⁴ of the removable filler section E.

In order to sustain the matrices X¹ against displacement from the hand stick F during a casting operation, there is provided, in the lower rail member F², an adjustable keeper plate F¹⁰ arranged for limited parallel movement into and out of engagement with the notches x⁴ in the matrices X¹ when the latter are composed in line in the hand stick. The keeper plate F¹⁰ is somewhat longer than the hand stick F and in its normal or retracted position extends beyond the left end thereof (looking from the front of the machine). The rail F² is made in two sections f¹, f² held in parallel spaced relation by a pair of spacer members f³ and the keeper F¹⁰ is mounted between the sections and formed with a corresponding pair of notches f⁴ straddling the spacers and somewhat larger in size to permit a limited endwise movement of the keeper member. When the hand stick is inserted in the transporter, the keeper F¹⁰ banks against the

block b^6 which is screwed and dowelled to the transporter front wall B^4 on the inner face thereof of just above the supporting ledge B^9 , and is moved thereby to the right and forced upwardly into active position wherein it engages in the notches x^4 in the matrices. This operation is effected by a pair of pins f^5 extending transversely across the space between the rail sections and acting upon the edges of a pair of inclined slots f^6 in the keeper member through which the pins f^5 pass, as the keeper is moved to the right relatively to the stick.

In Figs. 15, 16 and 17, there is illustrated a hand stick G for use with the special (Ludlow) matrices Z^1 . Like the hand stick F , it is provided with top and bottom rails G^1 , G^2 , fixed end walls G^3 , G^4 , and an adjustable end wall mechanism G^5 for applying clamping pressure on the line. In this stick, however, the matrices are inserted from the rear, the front faces of the ears z^2 banking against the upper and lower rails at the rear. As shown in Fig. 16, the front edges of the end walls G^3 , G^4 are provided at the top with notches G^6 similar to and for the same purpose as the corresponding notches F^9 in the hand stick F , while the lower edges of said end walls together with the bottom of the rail G^2 constitute an alining surface G^7 for the stick which rests upon the supporting ledge E^4 of the removable section E of the transporter. In the alining surface G^7 there is also provided a notch G^8 extending longitudinally of the stick, and which receives the upstanding keeper element E^5 of the removable section to prevent the stick from being displaced from the transporter during a casting operation. It will be noted also, that the end walls G^3 , G^4 , as well as the movable plate G^5 have rear extensions G^9 to conform to the rear portions of the matrices X^1 that extend beyond the rails.

The stick H (Fig. 18) for use with the large special matrices Z (also the "Ludlow" type) is in all respects similar to the stick G just described, except that the lower rail member H^2 is narrower than the corresponding rail member G^2 of the stick G , thus providing a larger space between the rail members to accommodate the larger matrices.

The hand stick J (see Fig. 22) for use with the large special matrices X is formed with a closed back plate J^1 of substantial thickness, end walls as in the hand sticks previously described, and a bottom rail member J^2 screwed to the back plate and having a projecting tongue J^3 at its upper edge to engage in the notches x^7 of the matrices X to prevent them from being displaced from the stick during a casting operation. In this instance, the upper rail member is dispensed with and the hand stick is maintained in the transporter by the rear wall B^5 thereof engaging in the notches x^9 provided in the front casting edges of the matrices and corresponding notches in the end plates of the stick. The removable section E is dispensed with when the hand stick J is used. The bottom of the back plate J^1 and of the bottom rail member J^2 constitute the alining surface of the stick and rest directly on the supporting ledge B^9 of the transporter head portion B^3 , the keeper B^{10} engaging in a notch J^4 provided in the lower front edge of the rail member J^2 to prevent the stick from being displaced from the transporter. If desired, the rear wall of the hand stick may be recessed as at J^5 to secure lightness.

75 The hand stick K for use with the regular

two-letter matrices Y (Fig. 19) is likewise inserted directly in the transporter B^3 without the use of the removable section E , and comprises generally the end walls K^1 as in the hand sticks previously described, and a back wall K^2 provided near its lower end with a pair of rails K^3 , K^4 to support the matrices Y either at the upper or lower casting levels. The back wall K^2 is also provided in its upper portion with a longitudinal recess K^5 of sufficient width to accommodate the upper ears y^1 of the matrices Y when composed either at the upper or lower level. When the regular linotype matrices Y are used, the transporter head B^3 is equipped with a removable auxiliary back plate B^{12} , detachably connected by means of a tongue and groove to the rear wall B^5 thereof. The plate B^{12} is wider than the rear wall B^5 so that the lower edge thereof, when the plate is attached, is just below the upper projecting ears y^1 of the matrices when supported by the lower ledge K^3 . The removable auxiliary plate B^{12} , shown in Fig. 19, is provided at its lower edge with a lateral extension b^{11} engaging beneath the front upper ears y^1 of the matrices to render additional support during casting. The bottom of the back wall K^2 constitutes the alining surface of the stick and rests directly upon the supporting ledge B^9 of the transporter and is held against displacement therefrom by the keeper plate B^{10} which engages the front of the back plate adjacent its lower edge.

The hand stick L (see Fig. 20), for use with the regular head-letter matrices Y^1 , is quite similar to the stick K just described, differing only in that there is provided but a single rail L^2 in the back plate L for supporting the matrices Y^1 and arranged at the same level as the upper rail K^4 in the stick K , since, as is well known, the head-letter matrices are always composed at the upper level in the commercial linotype machine. The recess L^3 adjacent the upper portion of the stick which receives the upper projecting ears y^1 of the matrices is narrower than the corresponding recess K^5 in the stick K , since matrices are composed at one level only in the stick L . The bottom of the back plate L^1 constitutes the alining surface for the hand stick which rests directly on the supporting ledge B^9 of the transporter, the back plate L^1 being somewhat thicker than the back plate K^2 of the sticks K , and provided at its lower front edge with a longitudinal recess L^4 to receive the keeper B^{10} . As is the case when the stick K is used, the back plate B^5 of the transporter head is equipped with a removable auxiliary plate B^{13} , detachably connected by means of a tongue and groove joint, and which likewise is wider than the back plate B^3 and extends below the lower edge thereof to a level corresponding to that of the under side of the upper projecting ears y^1 of the matrices Y^1 composed in the stick to lend additional support thereto.

At this point it may be stated that all of the hand sticks may be equipped adjacent their upper and lower edges with scales marked off in ems as an aid to the composer.

As previously stated, the stick with its composed line of matrices is alined with the transporter and inserted endwise therein from the right end. To facilitate this operation, there is provided a bracket M^1 secured to the table M and provided with a vertical front face M^2 and, when the hand sticks J , K and L are used (those for the regular matrices Y , Y^1 and the large special matrices X), they are placed with their alining surfaces in con-

fact with the table and with the casting edges of the matrices in contact with the front face M^2 of the bracket, in which position the sticks are in endwise alinement with the transporter. When the sticks F, G and H are used, however, (those wherein the special matrices X^1 , Z^1 and Z are composed) the transporter head B^3 is provided with the removable section E, and as a consequence such sticks must be positioned at a higher level to be in proper alinement for transfer. For this purpose, there is provided in the base of the bracket M^1 , a slideable plate M^3 adjustable from a position wherein its front edge m is flush with the vertical face M^2 (Fig. 22) to a position wherein its front edge is in line with the rear face of the removable section E (see Fig. 21). The plate M^3 is of the same thickness as the bottom portion E^2 of the removable section. Thus, in order to aline the sticks F, G and H at the proper level for transfer to the transporter, the removable section E being in place, it is necessary only to adjust the plate M^3 to its forward position, and place the sticks with their alining surfaces in contact therewith and with their casting edges in contact with the front face M^2 of the bracket M as in the case of the sticks previously referred to. The adjustment of the plate from one position to another is facilitated by a stud M^4 projecting from the top of the plate M^3 and through a slot M^5 provided in the lower portion of the bracket member M^1 .

Preparatory to the casting operation, and after the transporter has descended to present the line to the mold, the stick is clamped tightly between the vise jaws C¹, C² and is positioned thereby endwise so as to cause the line properly to register with the end walls of the mold slot. This operation is effected by a vertical reciprocatory wedge bar C³ through the medium of a short horizontal slide rod C⁴ against which the left hand jaw C¹ abuts.

The construction and operation of the wedge bar for causing the line to register with the mold slot is adequately set forth in my copending application, Serial No. 545,398, filed June 19, 1931, and need not be described in detail here again. Suffice it to say, when the bar C³ is raised, the jaw C¹ is forced positively thereby to the right or toward the opposing jaw C², whereas when the bar is lowered, the jaw C¹ is forced to the left or returned to its original position by resilient means not shown. The upward movement of the bar C³ (in the present instance a positive one) is limited by a stop screw C⁵ (see Figs. 1 and 3), banking against a bracket C⁶ which guides the rod C⁴, and hence the jaw C¹ is always moved a definite distance by the bar, so as to locate the left end of a line properly composed in the hand stick in registry with the left end of the mold slot.

The movement of the left hand jaw C¹ is imparted to the hand stick and thence through the line, the movable end wall F⁶ (assuming the stick F is in use), and the pin F⁷ to the right hand jaw C², and, if the line is of proper length, the right hand jaw is adapted to yield toward the right against the tension of a spring C⁷ which normally holds it towards the left, and offers the resistance necessary for the justification of the line. It will be recalled that the operator applies an initial clamping pressure to the line by means of the bushing F⁸ prior to the insertion of the stick in the transporter, but, as this is a manual adjustment, there is no way of telling whether or not the clamping pressure applied is sufficient. The right hand jaw C² acting through the pin F⁷ and the movable wall F⁶ automatically applies addi-

tional pressure independently of that applied by the bushing F⁸ in the event the initial pressure is not sufficient. In yielding, the jaw C² is adapted to actuate a safety pump stop lever C⁸ common to the commercial linotype machines, and which when actuated permits the cycle of operations to proceed, the active mold being moved up against the matrix line and the casting operation allowed to take place. If the pump stop lever C⁸ is not actuated by the yielding jaw C², the casting operation cannot proceed. The range of movement of the right hand jaw C² is in excess of that required to operate the pump stop lever, thus compensating for slight variations in the lengths of lines below the maximum length permitted by the hand stick. In other words, the arrangement is such, that the pump stop lever is operated through the line of matrices irrespective of the movement of the hand stick.

After the casting operation is completed, the first elevator ascends to the level of the table, and the stick ejected from the right hand end thereof (the end in which it was inserted), the opposite end being closed off for reasons of safety when the elevator is in its uppermost position by a vertical plate M⁶ suitably fastened to the table. The ejection of the hand stick is effected by a hand operable slide B¹³ (see Figs. 6 and 7) which includes a body portion b⁷ arranged to slide upon the upper face of the elevator head B³, a vertical handle b⁸ extending upwardly from the body portion, and a depending vertical portion b⁹ arranged to slide in the space between the front and rear walls B⁴, B⁵ of the elevator head and having a finger b¹⁰ at its lower end adapted to extend somewhat below the top edges of the upper rails of the hand sticks. With this arrangement, the slide B¹³ is always located to the left of the hand stick in the elevator and to eject the stick it is necessary only for the operator to grasp the handle b⁸ and push it to the right, whereupon the finger b¹⁰ engages the end of the hand stick and pushes it out of the transporter.

As described in my application, Serial No. 545,398, previously referred to, the special matrices X^1 are provided in their casting edges with intaglio characters formed thereon for common base alinement. Furthermore, the inner casting surfaces of the molds for use therewith, regardless of size, are all equidistant from the axis of the mold disc A, the molds being adjustable in the usual way for the different font sizes by the insertion of liners between the base and head portions of the mold and at the ends thereof. As a consequence, composed lines of matrices of different font sizes must be presented to their respective molds at different casting levels. Then, too, there is the so-called "high" and "low" alinement for the matrices X^1 depending upon the length of the lower case descenders. Thus in Fig. 29, there are represented four matrices, say of 48 pt. size, wherein the characters are formed for base alinement but wherein the datum line $u-u$ for the matrices 1 and 2 is lower down than the datum line $v-v$ of the matrices 3 and 4, due primarily to the difference in length of the descenders of matrices 2 and 4. Although the distance between the bottom of the letter P and the top of the letter A is the same in both cases (u¹=v¹) the distance u² (that between the top of the letter A in the matrix 1 and its lower alining surface) is greater than the corresponding distance v² of the matrix 3, and consequently a composed line of matrices 1, 2 must be presented

to the mold at a lower level than a composed line of the matrices 3, 4.

The special matrices Z and Z¹, likewise must be presented to the mold at different casting levels depending upon their size, but as the characters provided in the casting edges of these matrices are formed for center alinement, the difference in level at which composed lines of the different fonts are presented to the mold will vary from the difference in level at which corresponding sizes of the special matrices X¹ are presented.

The regular linotype matrices Y because of the double characters on their casting edges are presented to the mold at two different casting levels, but as the stick K in which they are composed is equipped with upper and lower rails it is necessary only to provide for arresting the elevator B at one level when the matrices Y are employed and the same level is used for the head-letter matrices Y¹.

The matrices X ranging between 72 pt. and 144 pt. are usually cast on a 72 pt. slug and consequently no special provision need be made for these.

In addition to the many different casting levels at which the matrices of the different forms and sizes must be presented to the mold, it may also be desired to cast large faces on slugs of smaller body sizes (slugs with overhanging faces) as for instance a 72 pt. face on a 12 pt. body size, and it may further be desired to form the body portion of the slug at either edge of the face or at any other intermediate point.

The means herein provided for locating the matrices of the different forms and various font sizes in proper casting relation to the corresponding molds, include a pair of duplicate banking blocks D¹, D², arranged to cooperate with the banking screws B¹¹ of the transporter B. Each of said blocks slopes continuously and evenly from the high point at the left to the low point at the right, so that by adjusting the blocks laterally of the transporter B, the latter may be arrested in its descent to position a composed line carried thereby at any desired casting level.

The blocks D¹, D² are carried by a long thin plate D³ slidably mounted, by means of retaining gibs or guideways D⁴, upon the vise cap D⁵ and capable of adjustment to any desired position beneath the banking screws B¹¹.

The machine is equipped with the usual control rod N of the "vise automatic" and in order that it may be actuated as required in any adjusted position of the blocks D¹, D², there is employed a third sloping block D⁶ (an exact duplicate of the blocks D¹, D²) carried by the plate D³ and hingedly mounted at the back in suitable bearings rising from said plate, and normally resting at the front upon the upper end of the rod N (Fig. 5).

As the plate D³ is adjusted to bring any point of the blocks D¹, D² beneath the banking screws B¹¹ of the transporter, the corresponding point of the block D⁶ will be positioned directly beneath the third screw B¹² in the overhead flange B² of the transporter, so that when the transporter is arrested in casting position by the banking of the screws B¹¹ upon the blocks D¹ and D², the screw B¹² will depress the blocks D⁶ and thereby actuate the rod N.

The plate D³ (see Figs. 1 and 26) is adjusted by means of a dial plate D⁷ fixed at the upper end of a stub shaft D⁸ rotatably mounted in a bracket D⁹ screwed to the vise cap D⁵, and having secured thereto, a pinion D¹⁰ meshing with a rack

D¹¹ fixed to the plate D³. The dial is held in its adjusted position by a pin d carried in a hole d¹ drilled in the bracket D⁹ and spring pressed into a groove d² in the peripheral edge of the dial plate. The force of the spring is ordinarily sufficient to cause the pin d to hold the dial against creeping, but where a number of recasts are to be made, the dial may be locked in position by a thumb screw d³ threaded into the hole d¹ at its outer end, and having a pin extension d⁴ arranged to engage the rear face of the pin d firmly to force the latter against the dial.

Two forms of dials are shown, the one represented in Figs. 23 and 24, being permanently fixed in place and having dial indications on one face only, and the other represented in Figs. 25 to 28 including a reversible dial plate d⁵, either face of which may be turned uppermost depending upon the matrices to be used. In the plate d⁵, there is provided a hole d⁶, for registration with a pin d⁷ on the body portion D⁷ of the dial element, so as to insure the proper positioning of the banking block members D¹, D², when any dial indication registers with a pointer d⁸. The pointer d⁸ is hinged to the bracket D⁹ so as to permit the removal and reversal of the plate d⁵.

On each dial face there is provided a scale graduated in type points starting from zero and running to 60. When the zero point of the scale is opposite the indicator d⁹, the highest points 30 of the banking blocks D¹, D² will register with the banking screws B¹¹ on the transporter so as to arrest the elevator in its uppermost position and, for any other position of the dial, the elevator will be arrested at a correspondingly lower 35 point, the dial and consequently the banking blocks between their maximum and minimum heights having a range of 60 pts. Consequently, when it is desired to offset the face of a slug from the body portion, as, for instance, in casting a 72 pt. face upon a 12 pt. body, the point scale will give an immediate indication of the amount of offset required to bring the body portion of the slug at any desired position with reference to the face thereof.

The outermost set of indications on the dial face shown in Fig. 23 are for use in connection with the special matrices Z and Z¹, whereas the inner set of indications are for use in connection with the special matrices X¹. Thus, when it is desired to cast a 60 pt. slug from the special matrices Z¹ (Ludlow type) 60 on the outer scale is set opposite the indicator d⁹, whereupon the banking blocks D¹ and D² will be positioned properly to arrest the elevator to bring the matrices 55 in proper alinement with the mold, and, in like manner, when it is desired to use 60 pt. matrices of the special type X¹, the mark 60^h or 60^l is used, as the case may be (depending upon whether the characters on the matrices are formed for 60 high or low alinement).

For the regular linotype matrices, a composed line is properly brought into register with the mold when the indication "Reg. Lino. Mats." is 65 turned to register with the indicator d⁹.

As stated heretofore, the dial shown in Figs. 24 and 25 is reversible, one face being marked with indications for use with the large special matrices X¹ and the regular linotype matrices, 70 whereas the reverse side is marked with indications for use with the special matrices Z and Z¹ (Ludlow matrices).

As a result of the banking block and dial arrangement, it will be seen that substantially all 75

types of matrices, regardless of their form or size, and which must be presented to the mold at different casting levels, may be very readily handled in the present machine.

- 5 In the accompanying drawings the invention has been shown merely in preferred form and by way of example, but it will be understood that many changes and modifications may be made therein and in its mode of application without departing from the spirit of the invention. It is to be understood, therefore, that the invention is not limited to any specific form or arrangement, except insofar as such limitations are specified in the appended claims.
- 10 15 Having thus described my invention, what I claim is:

1. In a slug casting machine adapted to be equipped with a plurality of interchangeable hand sticks differing in form to sustain matrices of different forms, a holder for presenting a selected hand stick in operative relation to the mold, said holder being alterable in form to accommodate the different hand sticks.
2. In a slug casting machine adapted to be equipped with hand sticks of different forms containing matrices of different forms, the combination of a holder for presenting a hand stick with its composed line of matrices in operative relation to the mold, and means for adapting the holder to support the hand sticks of different forms.

3. In a slug casting machine adapted to be equipped with hand sticks of different forms containing matrices of different forms, the combination of a holder for presenting a hand stick with its composed line of matrices in operative relation to the mold and having a pair of walls between which the hand stick is sustained, and a removable section cooperating with one of said walls for adapting the holder to support hand sticks of different forms.

4. A combination in accordance with claim 3, wherein the removable section is adapted to cooperate with the front wall of the holder, and wherein said front wall is provided with a lower supporting ledge and a keeper element arranged to engage the removable section or a hand stick directly when the removable section is not in use.

5. A combination in accordance with claim 3, wherein the removable section is provided with a lower supporting ledge and a keeper element arranged to engage a hand stick supported in the holder.

6. In a slug casting machine adapted to be equipped with hand sticks of different forms containing matrices of different forms, the combination of a holder for presenting a hand stick with its composed line of matrices in operative relation to the mold and being provided with front and rear walls, a removable section for one of said walls for adapting the holder to support hand sticks of different forms, and means for detachably securing the removable section against endwise displacement in the holder.

7. In a slug casting machine adapted to be equipped with hand sticks of different forms containing matrices of different forms, the combination of a holder for presenting a hand stick with its composed line of matrices in operative relation to the mold and being provided with front and rear walls, a removable section for one of said walls for adapting the holder to support hand sticks of different forms, and means including a spring detent arranged in the holder

and detachably securing the removable section against endwise displacement in the holder.

8. In a slug casting machine, the combination of a holder for presenting a composed line of matrices in operative relation to the mold, a hand stick in which the matrices are composed and slideable endwise into the holder, and means for ejecting the hand stick from the holder after a casting operation.

9. In a slug casting machine, the combination of a holder for presenting a composed line of matrices in operative relation to the mold, a hand stick in which the matrices are composed and slideable endwise into the holder, and a hand operable sliding element for ejecting the hand stick from the holder after a casting operation.

10. In a slug casting machine, the combination of a holder for presenting a composed line of matrices in operative relation to the mold and comprising front and rear walls between which a hand stick supporting the composed line of matrices is adapted to be positioned, and means including an element slideable between said walls and arranged to engage the hand stick whereby the latter may be ejected from the holder.

11. In or for a slug casting machine, a matrix composing hand stick equipped with means for preliminarily exerting pressure endwise on a line of matrices composed therein to hold them in the hand stick, and with means operable by one of the regular organs of the machine and independently of the first mentioned means for exerting pressure endwise on the line preparatory to the casting operation.

12. In or for a slug casting machine, a matrix composing hand stick equipped with an adjustable end wall, means for manually adjusting the wall to clamp a line of matrices in the hand stick, and means operable by one of the regular organs of the machine and independently of the first mentioned means for exerting clamping pressure on the line preparatory to the casting operation.

13. In or for a slug casting machine, a matrix composing hand stick equipped with an adjustable end wall, a manually operable screw for adjusting the wall to clamp a line of matrices in the hand stick, and means also associated with the adjustable end wall and operable by one of the vise jaws of the machine for exerting clamping pressure on the line preparatory to the casting operation and independently of the first mentioned means.

14. In a slug casting machine, the combination of a hand stick wherein a line of matrices is composed, a holder for presenting the hand stick with its composed line of matrices in operative relation to the mold, the usual pump stop lever, and means acting through the line when of proper length and irrespective of the hand stick to operate the pump stop lever and permit the casting operation to proceed.

15. In a slug casting machine, the combination of a hand stick wherein a line of matrices is composed and equipped with a movable end wall, a holder for presenting the hand stick with its composed line of matrices in operative relation to the mold, the usual pump stop lever, and means acting through the movable end wall when the line is of proper length but independently of the movement of the hand stick to operate the pump stop lever and permit the casting operation to proceed.

16. In a slug casting machine equipped with

the usual vise jaws and pump stop lever, the combination of a hand stick wherein a line of matrices is composed, a holder for presenting the hand stick with its composed line of matrices in operative relation to the mold and between the vise jaws, means for moving one of said jaws to justify the line, and means acted upon by the line and operating independently of the movement of the hand stick to actuate the pump stop lever and permit the casting operation to proceed.

17. In or for a slug casting machine, a matrix composing hand stick for matrices equipped with notches in at least one of the edges thereof and having one of its fixed walls provided with a slidably adjustable member adapted to engage in the notches formed in the matrices composed in the hand stick to prevent disengagement of the matrices from the hand stick during casting.

18. In a slug casting machine, the combination of a matrix composing hand stick for matrices equipped with notches in at least one of the edges thereof and being provided with a keeper element adapted to be moved into engagement with the notches formed in the matrices composed therein, and means for effecting such movement of the keeper element as the hand stick is inserted in the machine.

19. In or for a slug casting machine, a matrix composing hand stick for supporting a composed line of matrices in a holder for presentation to the mold and having one of its fixed walls provided with a relatively movable member adapted to engage in notches formed in the alining edges of the matrices composed therein to prevent disengagement of the matrices from the hand stick during a casting operation.

20. In a slug casting machine having a holder for presenting a composed line of matrices supported in a hand stick in operative relation to the mold, and wherein the holder is equipped with a removable section for adapting it to support hand sticks of different forms, the combination of a table for alining the hand stick with the holder for transfer thereto, and means for changing the transfer level of the hand sticks depending upon whether the holder is used with or without the removable section.

21. In a slug casting machine having a holder for presenting a composed line of matrices supported in a hand stick in operative relation to the mold, and wherein the holder is equipped with a removable section for adapting it to support hand sticks of different forms, the combination of a table for alining the hand stick with the holder for transfer thereto, and a plate adjustable to active position to support the hand sticks at one transfer level when the holder is equipped with the removable section, and adjustable to inactive position to permit the hand sticks to be supported at a different transfer level when the holder is not equipped with the removable section.

22. In a slug casting machine adapted to be equipped with matrices presentable to the mold at different casting levels, the combination of a vertically movable transporter for presenting a

composed line of matrices to the mold, and means adjustable at the will of the operator for arresting the transporter at an infinite number of positions between the upper and lowermost casting levels.

23. In a slug casting machine adapted to be equipped with matrices presentable to the mold at different casting levels, the combination of a vertically movable transporter for presenting a composed line of matrices to the mold, and means including an adjustable banking block presenting an infinite number of levels throughout its range of adjustment for arresting the transporter at the desired casting level.

24. In a slug casting machine adapted to be equipped with matrices presentable to the mold at different casting levels, the combination of a vertically movable transporter for presenting a composed line of matrices to the mold, and means including an adjustable banking block having a constant slope for arresting the transporter at any desired casting level.

25. A slug casting machine in accordance with claim 23, wherein the means including the adjustable banking block is provided with a scale graduated in type points for assisting the operator in making the desired adjustments.

26. In a slug casting machine adapted to be equipped with matrices of different forms, and presentable to the mold at different casting levels depending upon the form of the matrices and the size of the characters formed in the casting edges thereof, the combination of a vertically movable transporter for presenting a composed line of matrices to the mold, and adjustable mechanism for arresting the transporter at the desired casting level, said mechanism including differently graduated dials, interchangeable in position with each other in accordance with the form of the matrices in use.

27. In a slug casting machine adapted to be equipped with matrices of different forms, and presentable to the mold at different casting levels depending upon the form of the matrices and the size of the characters formed in the casting edges thereof, the combination of a vertically movable transporter for presenting a composed line of matrices to the mold, and adjustable mechanism for arresting the transporter at the desired casting level, said mechanism including dial means having differently graduated scales for the different forms of matrices and a common pointer for the different scales.

28. In or for a slug casting machine, a matrix composing hand stick comprising fixed side and end walls, a line clamping member adjacent one fixed end wall, a bushing threaded in the said fixed end wall and arranged to engage the line clamping member, and a pin attached to the line clamping member and projecting through the bushing.

29. A matrix composing hand stick as in claim 28, including a retaining element also carried by the fixed end wall and arranged to limit the outward movement of the threaded bushing.
